UNITED STATES PATENT OFFICE.

WILLIAM THOMAS CROSS, OF WHITEVILLE, TENNESSEE.

HORSE-POWER.

SPECIFICATION forming part of Letters Patent No. 317,519, dated May 12, 1885.

Application filed March 21, 1885. (No model.)

To all whom it may concern:

Be it known that I, WILLIAM T. CROSS, a citizen of the United States, residing at Whiteville, in the county of Hardeman and State of Tennessee, have invented a new and useful Improvement in Horse-Powers, of which the following is a specification, reference being had to the accompanying drawings.

My invention relates to horse-powers adapted more especially for use in running cotton-gins; and it has for its object to provide a device of this character which shall combine simplicity of construction with durability, ease of operation, and general efficiency.

The invention consists in the improved construction and combinations of parts, herein-after fully described, and pointed out in the claim.

In the drawings, Figure 1 is an elevation of a horse-power constructed in accordance with my invention. Fig. 2 is a plan view with the top of the framing removed, and Fig. 3 is a section on the line *x x* of Fig. 2.

In the accompanying drawings, in which like letters of reference indicate corresponding parts in all the figures, A represents a vertical shaft, which in this case is mounted and has bearing in top and bottom strips, B C, which are supported by vertical posts or uprights D.

Upon the shaft A is mounted a grooved pulley or band wheel, E, and secured to said shaft below the wheel E are bars F, which may be provided with any suitable arrangement of draft appliances. At one corner of the frame are provided posts or uprights G, between which is journaled a band-wheel, H, which is connected by a band, I, with a somewhat smaller band-wheel, J, mounted in brackets K upon the top B, the belt passing to said small band-wheel J through a hole or opening in said top.

Upon the shaft of the band-wheel H is a pulley, L, which is connected with the grooved wheel E by a strap or belt, a.

Upon the strap a is located a pulley, b, hav-

ing bearing in a bracket, c. The said pulley is located upon the strap or band a adjacent to the point at which the latter strikes the pulley L and guides said strap or band thereto. 50

M represents uprights, which are diagonally arranged with regard to the uprights G, and between said uprights is mounted an idler, e.

Secured to the bracket c is a cord, f, carrying a weight, g, at its end, said cord passing 55 over the idler e.

The operation is as follows: Motion is imparted to the wheel E by turning the shaft A and the band-wheel H through the medium of the pulley L and strap a, connecting the same with the band-wheel E. The pulley b on the strap or band a serves to guide the latter to the pulley L and prevents any possibility of its becoming detached, and by the employment of the weighted cord the bracket 60 is held in place and the strap or band a held taut, thus preventing it from slipping upon the wheel E or pulley L.

The power before described is simple in its construction, may be built at a slight cost, is 70 thoroughly efficient and easy in its operation, and strong and durable.

Having fully described my invention, what I claim as new, and desire to secure by Letters Patent, is—

The combination, with an upright shaft having a band-wheel thereon, a shaft having a band-wheel and pulley thereon, a shaft located above the frame and carrying a band-wheel, a strap connecting the band-wheel E and pulley L, a pulley on said strap, an idler mounted in posts or uprights, and a cord carrying a weight at its end, said cord being connected with the bracket of the pulley b, substantially as set forth. 75

In testimony that I claim the foregoing as my own I have hereto affixed my signature in presence of two witnesses.

WILLIAM THOMAS CROSS.

Witnesses:

J. Y. HUNDLEY,
A. J. COATES.
